STEAM AND HOT WATER HEATING
BOILER

Dawson Conekin, Philadelphia, Pa.

Application June 12, 1935, Serial No. 26,282

6 Claims. (Cl. 122—226)

The present invention relates to improvements in boilers as used in steam, hot water and vapor heating systems, and has for its object the provision of an apparatus in which a series of short coils of an easily replaceable nature and a type low in cost and maintenance, are so utilized as to effectively and efficiently operate throughout a lengthy life.

A further object of the invention is an arrangement and apparatus in and by which coils of a cast nature, more particularly of the vertical sectional radiator type, may be effectively and efficiently utilized.

With the foregoing in mind it is believed the further objects as well as the resulting advantages of the present invention, may be fully understood and appreciated from the following description and the accompanying drawings, disclosing the best mode so far devised for carrying the invention into practice.

In the accompanying drawings, which form a part of this specification,

Figure 1 is a side elevation of the improved boiler, partly broken away and in section.

Figure 2 is a rear elevation, partly broken away and in section.

Figure 3 is a horizontal section taken therethrough along about the line of the top of the combustion chamber, on line 3—3 of Figure 1.

Figure 4 is a similar view taken on a line 4—4 of Figure 2 through the intermediate heater units, and

Figure 5 is a vertical sectional view from front to rear taken on line 5—5 of Figure 2.

Referring now to these figures, there is shown a vertically disposed rectangular boiler 10 having therein a combustion chamber 11 to which access is had through a front door 12. While it is possible to use any desired means of producing heat by combustion in chamber 11, such as oil and gas, the furnace is shown with a space below the combustion chamber for use as an ash pit 13 in case solid fuel is used, necessitating a grate (not shown) between the combustion chamber 11 and the ash pit 13. A front door 14 provides for access to the ash pit 13.

Within the combustion chamber 11 single, cast vertical radiator units 15 are arranged parallel with, and adjacent to, the side walls of the boiler, these units being of a height approximately that of the combustion space. At the back of the combustion chamber are two single, cast vertical radiator type units 16 parallel with and adjacent to the rear wall, which are of substantially greater height and project at their upper ends approxi-

mately level with the upper ends of the intermediate heater units 17.

Above the combustion chamber, the internal area of the furnace is substantially fully taken up by the intermediate heater units 17 and the upper preheater units 18 and both of these banks of heating units consist of vertical sectional cast coils of the radiator type arranged in closely contiguous front and rear rows as plainly seen in Figures 1 and 5.

The upper portions of the side units 15 of the combustion chamber 11 are connected by short pipes 19 with the lower portions of the intermediate heater units 17 as plainly seen in Figure 1, and the lower portions of these side units 15 as well as the lower portions of the rear units 16 of the combustion chamber are connected, by branch pipes 20, to pipes 21 leading downwardly from the upper ends of the upper preheater units 18.

Return pipes 22 lead the return flow of the system or the water of condensation to the lower portions of the preheater units, and feed pipes 23 for the system lead from the upper portions of the intermediate heater units 17. To the feed pipes 23, which in a steam system lead to a suitable steam drum (not shown), the upper ends of the rear vertically elongated units 16 of the combustion chamber are connected by pipes 24, and pipes 25 connect the extreme upper portions of the pipes 21, supplying the preheated fluid to the combustion chamber units 15 and 16, to the outflow or system feed pipes 23 so that in heating hot water, steam, if any, may flow directly from these units 16 and pipes 21 into the system feed pipes 23.

As seen particularly in Figure 1, clean-out doors 26 and 27 normally give access to the upper preheater units 18 and the intermediate heater units 17 so that they may be easily maintained in a clean condition of maximum efficiency, and it is obvious any suitable inlet may be provided for replenishing the water of the system and any suitable outlet for draining the same.

In operation fluid returning to the boiler through the return pipes 22, is given a preheating in its passage through the upper preheating units 18 and when so preheated, passes downwardly through the pipes 21 to the lower portions of the single heater units 15 and 16 of the combustion chamber. The water heated in units 15, passes through the pipes 19 into the lower portions of the intermediate heater units 17 and after heating therein flows outwardly through the feed pipes 23 into the heating system, or steam drum.

Water heated in the vertically elongated combustion chamber units 16 passes outwardly through the upper outlet pipes 24 thereof directly into the system feed pipes 23 and in this way 5 an effective and efficient arrangement is completed with the utilization of cast units of the vertical sectional radiator type throughout, insuring long life, and ready repair and substitution of parts.

10 What is claimed is:

1. A boiler consisting of a shell having a combustion chamber in its lower portion, a series of single, cast radiator units lining said chamber, upper and intermediate series of vertical cast 15 radiator units occupying approximately the full area within the shell above the combustion chamber and of which the intermediate series of units are fed from said combustion chamber units, feed pipes leading from the intermediate series of 20 units, return pipes connected to the upper series of units for preheating the return fluid, and fluid feed connections between said upper preheating units and the said units of the combustion chamber.

25 2. A boiler having a combustion chamber and cast radiator units disposed around said chamber, upper and intermediate series of vertical cast radiator units similarly extending across the full space above the combustion chamber, the units of each series being connected and communicating with one another, feed pipes leading from, and connected to, the upper portions of the intermediate series of units, return pipes connected to the lower portions of the upper 30 series of units for preheating the return fluid, feed connections between the upper portions of the upper preheating units and the lower portions of the combustion chamber units, and feed connections between the upper portions of the 35 combustion chamber units and the lower portions of the intermediate series of units.

40 3. A boiler, comprising upper and lower sets of horizontally arranged vertical cast radiator type units, a feed pipe leading from the lower set of units, a return pipe leading to the upper set of units, and units of a similar nature arranged adjacent to a combustion space below said sets of units said combustion space units having a supply connection leading thereto from

the upper set of units and also having a feed connection leading therefrom to the lower set of units, and said combustion space units including certain units upstanding along the lower set of units and directly connected to the feed pipe. 5

4. A boiler, comprising upper and lower sets of horizontally arranged vertical cast radiator units, a feed pipe leading from the lower set of units, a return pipe leading to the upper set of units, and units of a similar nature arranged 10 at the sides and rear of a combustion space below the sets of units and having supply connections leading from said upper units, the units at the sides of the combustion space having feed connections leading to the intermediate units, and 15 the units at the rear of the combustion space upstanding along the lower set of units and directly connected at their upper portion with the feed pipe.

5. A boiler, comprising a shell having a lower 20 combustion chamber, cast upright radiator units at the sides of said chamber, horizontal series of vertical cast units of radiator type across the space above said chamber, pipes connecting the upper portions of the combustion chamber 25 units with the lower portions of said horizontal series of units, a feed pipe leading from the upper portions of said horizontal series of units, a second horizontal series of units similar to, and arranged above, said first series, a pipe connecting the upper portions of the second series 30 of units with the lower portions of the combustion chamber units, and a return pipe connected to the lower portions of said second series of units. 35

6. A boiler comprising upper and lower horizontal sets of vertical cast radiator units, feed pipes leading from the upper portions of the opposite ends of the lower set of units, return pipes leading to the lower portions of the opposite ends of the upper set of units, units of a similar nature arranged adjacent to a combustion space below said sets of units, supply pipes leading to said combustion space units from the opposite upper ends of the upper set of units, 45 and feed pipes leading from said combustion space units to the opposite lower ends of the lower set of units. 40
